US0D1038136S

(12) **United States Design Patent** (10) **Patent No.:** **US D1,038,136 S**
(45) **Date of Patent:** **** Aug. 6, 2024**

(54) **ELECTRONIC DEVICE CLIP**

(71) Applicant: **JS Design Concepts Limited**,
Termonfeckin Louth (IE)

(72) Inventor: **Joe Shortt**, Termonfeckin Louth (IE)

(73) Assignee: **JS DESIGN CONCEPTS LIMITED**
(IE)

(**) Term: **15 Years**

(21) Appl. No.: **29/836,902**

(22) Filed: **Apr. 29, 2022**

Related U.S. Application Data

(62) Division of application No. 29/750,205, filed on Sep. 11, 2020, now Pat. No. Des. 956,767.

(57) **CLAIM**

The ornamental design for an electronic device clip, as shown and described.

DESCRIPTION

FIG. 1 is a top, perspective view of the electronic device clip according to the new design.

FIG. 2 is a bottom, perspective view of the electronic device clip according to the new design.

FIG. 3 is a front view of the electronic device clip according to the new design.

FIG. 4 is a rear view of the electronic device clip according to the new design.

FIG. 5 is a right side view of the electronic device clip according to the new design.

FIG. 6 is a left side view of the electronic device clip according to the new design.

FIG. 7 is a bottom view of the electronic device clip according to the new design; and,

FIG. 8 is a top view of the electronic device clip according to the new design.

1 Claim, 5 Drawing Sheets
